UNITED STATES PATENT OFFICE.

JACOB M. HUNTER, OF CHICAGO, ILLINOIS, ASSIGNOR TO WILLIAM T. BLAINE, OF CHICAGO, ILLINOIS.

COIN-CONTROLLED X-RAY MACHINE.

SPECIFICATION forming part of Letters Patent No. 695,154, dated March 11, 1902.

Application filed March 22, 1901. Serial No. 52,381. (No model.)

To all whom it may concern:

Be it known that I, JACOB M. HUNTER, a citizen of the United States, residing at Chicago, in the county of Cook and State of Illinois, 5 have invented new and useful Improvements in Coin-Controlled X-Ray Machines, of which the following is a specification.

My invention relates particularly to coin-controlled X-ray machines in which a fluoroscope is used in combination with X-ray exciting apparatus, though the invention is not limited to machines equipped with fluoroscopes.

My primary object is to provide a practical 15 coin-controlled X-ray machine which can be used by the public generally for experimenting with or noting phenomena of the so-called "X-rays."

My invention is illustrated in its preferred 20 form in the drawings, in which—

Figure 1 is a vertical section of a coin-controlled X-ray machine, the section being taken parallel to the front of the casing; Fig. 2, a vertical sectional view, the section being 25 taken perpendicular to the front of the casing; Fig. 3, an enlarged broken sectional view showing a portion of one side of the casing and the operating handle or lever of the coin-controlled mechanism; Fig. 4, an enlarged 30 broken section showing a coin-actuated wheel and a manually-operated wheel coacting therewith; Fig. 5, a detached view of a convenient form of Crookes tube at which the X-rays are produced; Fig. 6, a view in side 35 elevation of the detached coin-controlled mechanism; Fig. 7, a plan view of the same; Fig. 8, a section taken as indicated at line 8 of Fig. 7; Fig. 9, a sectional view taken as indicated at line 9 of Fig. 7 and showing a 40 face view of the coin-actuated wheel employed, the parts being shown in the position which they occupy prior to the introduction of a coin; Fig. 10, a similar view illustrating the position of the parts after the manually- 45 actuated wheel has been rotated, and through the medium of a coin has moved the coin-actuated wheel; Fig. 11, a view of that side of the manually-actuated wheel which is adjacent to the coin-actuated wheel.

50 A represents a casing of any suitable form, the same being provided with a fluoroscope-

support A', bearing a fluoroscope A² and provided also with an instruction-card support A³; B, a Crookes tube supported by a clamp B' attached to bracket B², projecting from an internal surface of the casing; C, an induction-coil of common construction, the same being provided with a vibrator or current-interrupter a and primary-circuit binding-posts a' a²; D, batteries equipped with conductors b b', and E coin-controlled mechanism through which the primary circuit is completed when the machine is operated through the medium of a coin.

The coin-controlled mechanism comprises, 65 preferably, a frame portion E', a shaft E², a crank or lever E³ outside the main casing and fixed to said shaft; a manually-actuated wheel E⁴, fixed to the inner end of said shaft and provided with a curved coin-engaging lug c; 70 an adjacent coin-actuated wheel E⁵, through which the shaft E² loosely extends, said last-named wheel being provided with curved lugs c' c², affording between them a channel c³, within which the lug c works idly when no 75 coin is interposed; a spring E⁶, which serves to hold the wheel E⁵ with the lug d thereon in engagement with a stop with which the frame part E' is provided; E⁷, a spring connected with a lug f, projecting from the coin-wheel E⁵ and with a part of the stationary frame E'; F, a shaft parallel to the rock-shaft E²; F', a pinion loosely journaled on the shaft F and provided with an arm F²; F³, a pawl held by a spring g and bearing upon a ratchet-wheel F⁴, which is fixed upon the shaft F; F⁶, a gear-train actuated from a gear F⁵ and communicating motion to a fan or regulator F⁷; F⁸, a contact-wheel fixed to the shaft F and provided peripherally with a recess h; F⁹, a 80 contact-spring provided with a point h', which projects into the notch or recess h of the contact-wheel F⁸ when said contact-wheel is at rest and which bears upon the peripheral surface of said contact-wheel when said wheel 85 is in motion; G, a spring locking device provided with a lug or point k, Fig. 4, which rides upon a cam k', with which the coin-actuated wheel is provided, and serves to engage one of the teeth k², with which said 90 coin-wheel is equipped throughout a portion of its circumference, and provided also with 95 100

a lug k^3 , having a beveled surface k^4 , which serves to engage a shoulder k^5 , with which the manually-operated wheel is provided, thereby to release the coin-actuated wheel 5 from the lug k when the manually-operated wheel returns to its position of rest under the influence of its spring; H , a coin-chute leading to the upper portion of the coin-actuated wheel; H' , a coin-discharge passage leading 10 from the coin-controlled mechanism, and H^2 a coin-box with which the passage H' communicates.

When in rest, the lug c and the lugs $c' c'$ occupy the relative positions shown in Fig. 9, 15 and a coin-passage l is afforded, leading from the base of the coin-chute H to the lower portion of the lug c . The lower end of the lug c' projects beyond the lower end of the lug c^2 , affording a rest for the coin l . When the 20 handle E^3 is moved in the direction indicated by the arrow in Fig. 3, the wheel E^4 is, through the medium of the shaft E^2 , moved in the direction indicated by the arrow in Fig. 6. If no coin is interposed, the wheel E^5 will 25 remain at rest during actuation of the shaft E^2 . If, however, a coin be interposed, the lug c will force the same against the lug c^2 and cause the wheel E^5 to make a partial rotation. After such action the wheel E^5 would occupy 30 the position shown in Fig. 10, and upon release of the handle E^3 the wheel E^4 would at once return to its former position, allowing the coin to fall into the discharge-passage H' .

When the coin-actuated wheel E^5 is moved 35 in the direction indicated by the arrow in Fig. 6, as through the medium of a coin, the spring E^6 is extended and the gear-sector on the coin-actuated wheel, through the medium of the pinion F' , imparts a complete revolution to 40 the arm F^2 upon its shaft F , the pawl F^3 being carried completely around the ratchet-wheel F^4 and caused to take a new hold upon the single tooth or shoulder with which said ratchet-wheel is shown provided. The spring 45 E^7 now contracts, imparting a comparatively slow movement to the pinion f' and arm F^2 in the direction indicated by the arrow in Fig. 8. This movement is retarded by the action of the fan F^7 . The shaft F rotates with 50 the ratchet-wheel F^4 , thereby imparting motion to the contact-wheel F^8 . This brings the periphery of said contact-wheel into contact with the point h' , and this contact continues during a revolution of said contact-wheel, 55 after which the mechanism comes to rest in the position indicated in Fig. 6. As will be understood from Fig. 4, the lug k drops into engagement with a tooth k^2 of the gear-sector with which the coin-wheel is provided after 60 the cam k' has been carried around far enough to pass completely from engagement with or support of said lug. When the crank E^3 is released after manual actuation thereof, the wheel E^4 returns quickly to its position of rest, and as the shoulder k^5 engages the inclined surface k^4 the device G is thereby lifted, 65 removing the lug k from engagement with

the tooth of the coin-actuated wheel. This leaves the coin-actuated wheel free to be returned slowly to its position of rest under the action of the spring E^7 .

The operation of the machine will be readily understood from the foregoing description. The construction of the coil C , the connection of the secondary winding thereof with the 75 Crookes tube, the common form of circuit-interrupter for the primary circuit, and the construction and application of a condenser to the primary circuit or a shunt thereof are all well understood. The use in general of a 80 fluoroscope in connection with an X-ray apparatus is well understood. In the present construction the support A' is of box form, having open ends allowing a hand or any small article to be readily inserted between 85 the fluoroscope-screen m , which may be of tungstate of calcium or any other suitable chemical. The casing-front, if made of hard wood, is provided with an opening m' , which is situated between the screen m and the 90 Crookes tube.

It will now be understood that the machine may be operated by inserting a coin into the coin-chute H and actuating the handle E^3 , thereby setting the spring E^7 , and that during 95 the rotation of the contact-wheel F^8 under the action of the spring E^7 the primary circuit is closed during approximately one revolution of said contact-wheel. The period of revolution of said contact-wheel obviously may be 100 changed as desired. Immediately upon the completion of the primary circuit the induced current of the secondary circuit begins the excitation of X-rays, and by the time the contact-wheel F^8 has completed a small fraction 105 of one revolution the X-rays are being produced in great enough abundance to enable the operator to view the representation or shadow of the bony structure of the hand or of any article impervious to the passage of 110 X-rays, which may be placed between the fluoroscope-screen and the source of the X-rays.

Changes in details of construction within the spirit of my invention may be made. 115 Hence no limitation is to be understood from the foregoing detailed description except as shall appear from the appended claims.

What I claim as new, and desire to secure by Letters Patent, is—

1. In a machine of the character described, the combination of a casing, X-ray apparatus installed therein, including a coil having a primary circuit, and coin-controlled mechanism for completing said primary circuit, comprising, in combination, a rotatable contact-wheel, a coin-actuated wheel communicating motion thereto, and a manually-operated coin-engaging device which serves, through the medium of a coin, to move said coin-actuated wheel, substantially as described. 125

2. In a machine of the character described, the combination of a casing, X-ray apparatus installed therein, and coin-controlled mech-

anism for controlling the operation of said X-ray apparatus, comprising a rotating contact-maker, a coin-actuated wheel through the medium of which the said contact-maker is moved, a shaft extending loosely through said wheel, a spring connected with said wheel, a coin-engaging wheel fixed to the inner end of said shaft and located adjacent to said coin-actuated wheel, a coin-passage between said 5 wheels, and an operating-handle connected with said shaft and located outside said casting, substantially as described.

3. In a machine of the character described, the combination of a coin-actuated wheel provided with lugs c' , c^2 , a shaft extending loosely

through said wheel, a wheel fixed to the inner end of said shaft and provided with a lug c located to pass between the lugs c' , c^2 when no coin is interposed, a coin-passage between said wheels permitting a coin to pass into contact with the adjacent ends of said three lugs, a spring connected with said coin-actuated wheel, and an operating-handle connected with the outer end of said shaft, substantially as described. 20

JACOB M. HUNTER.
